HELIX COMBINATION WOOD-CARVING
ATTACHMENT

Percy B. Pyle, Lewistown, Pa.

Application July 29, 1933, Serial No. 682,869

5 Claims. (Cl. 142—26)

The object of my invention is to provide an attachment for cutting or impressing ornamental designs upon a surface. This particular embodiment thereof has been selected for the purpose of illustrating an attachment for forming the peripheral surfaces of such articles as wood moldings, novelties, etc. Such ornamentations are commonly referred to in this art as "fluting". In the past all such fluting has been done by the use of several machines requiring different attachments for irregular surfaces and to make the several designs. The present invention contemplates an attachment, to fasten on the longitudinal section of the improved lathe and synchronized to the lathe spindle. Said attachment provides means for cutting convexo-concave helical lines or grooves on the straight, taper, ovate-oblong or parallel, peripheral surface; producing an ornamentation to give convoluted-ogee designs, and many diamond shape designs; a combination of straight, parallel designs. My attachment consists essentially of a flexible shaft, compound rest rotating and traversing devices equipped with suitable differential indexing mechanism, pull-pin, and means for suitably revolving the work to the fluting cutters; together with novel stops, bearing and controlling devices for the attachment.

I attain these and other objects of my invention by the mechanism illustrated in the accompanying drawings, in which—

Figure 1 is a top plan view of my invention;

Fig. 2 is a top plan of the control carriage which is movable on the rods 1 and which carries the convoluted bar 24;

Fig. 3 is a view partly in side elevation and partly in vertical section on the line 3—3 of Fig. 2 illustrating the cutter controlling mechanism;

Fig. 4 is a detail elevational view of the pattern control convoluted bar showing a bar having a right hand twist;

Fig. 5 is an end elevation of the gears and disk mechanism controlled by the convoluted bar and interchangeable gear adapter;

Fig. 6 is a horizontal section on the line 6—6 of Fig. 5;

Fig. 7 is a detail view of members 38 and 39;

Fig. 8 is a detail view of member 40; and

Fig. 9 is a perspective view of the entire apparatus.

Like numerals designate like parts in each of the several views.

Referring to the accompanying drawings, the device is an attachment to a lathe having end frame members 2, supports 23 (as shown in Fig.

5), and longitudinal frame members 4. The machine has a pair of spaced parallel rods 1 on which a novel control carriage 31 is slidably mounted. I provide a combination tool rest and guide 3 laterally adjustable on the frame bars 4 and supporting the guide rods 1 as shown in Figs. 1 and 9. Member 5 designates the conventional lathe tail stock having a work engaging end 6; and member 8 is the lathe head stock having the work engaging end 7.

I provide a disk 9 having an integral hub member 11, as shown in Figs. 1 and 6, and also having a series of spaced perforations disposed annularly around the disk. Disk 9 is rotatably mounted in casing 15. Casing 15 is provided with the spring pressed locking or pull pin 13 having the pull knob 12 and spring 14. Pin 13 may engage any of the perforations 10. I provide set screw 16 detachably securing gear 17 to member 15. I provide a second gear 18 arranged to mesh with gear 17. Gear 18 is provided with a slot 19 to receive the convoluted bar 25 or the reversely convoluted bar 24, either of which bars may be used, depending on whether a right hand twist or a left hand twist is desired on the tool which operates on the piece W to be ornamented. As shown in Figs. 1 and 9, I provide a series of spaced perforations 21 in spiral bars 24 and 25.

Referring to Fig. 6, I provide a threaded ring 20 secured to gear 18 by suitable screws, bolts, or rivets 16a. I also provide an inner ring or adapter 20a as shown in Fig. 6 threaded as shown in ring 20 and recessed to receive the ring 20b. I also provide a suitable stop lock screw or bolt 20c as shown in Figs. 5 and 6.

Referring to Fig. 6 hub 11 is provided with a suitable set screw 22 to releasably engage the work supporting element 7. Referring to Fig. 2, the bar 24 (or bar 25 as the case may be) is secured to the control carriage 31 by screw or 40 stud 26.

Referring to Figs. 2 and 3, I provide a screw 30 seated in ring 35, and having an operating handle 28 affixed to its upper end. Ring 35 terminates in depending rods 34 which are mounted in the control carriage 31.

For certain work, positioned in place of screw 30 I provide and substitute a pin 29 having a reduced portion 38 on which is mounted a spring 39 of the diameter shown and which is retained on the pin by suitable means 39a such as the cotter pin and washer shown. I provide a compound rest 36 swivelly mounted on ring 35 and adapted to be fastened in any desired position by the set screw 27. As shown in Fig. 3, the control car-

riage 31 is provided with slits and channels to permit of slidably mounting the carriage on rods 1. I also provide suitable bolts 32. I also provide a guideway lock nut and screw 33 securing control carriage 31 to guide rods 34; or permitting the carriage 31 to slide loosely on said rod when not fastened in an adjusted position.

As shown in Fig. 1, I provide a flexible shaft 43 which drives the cutter 40 having a casing 41 and holder 42 for member 41 is supported by the compound rest 36 and detachably secured thereon by bolt 37.

I provide suitable stop members for the control carriage, such as the stop bolt 44 shown in Fig. 2 and which may be mounted in any one of the perforations 21. I may also provide for quick adjustment suitable stops 45 slidably mounted on one of the two rods 1 and having set screws for fastening the stops in an adjusted position.

20 The element on which ornamental work is to be performed is designated in the drawings as "W".

In using the apparatus the appropriate bar 25 or 24 may be mounted in the machine according to whether it is desired to cut a groove on a piece of work in a right hand direction or in a left hand direction, the metal bar 25 having a right hand twist and the metal bar 24 a left hand twist.

30 The grooves in element W are made by the cutter 40 which is operated by flexible shaft 43, the holder element 41 being carried by the swivelly mounted compound rest 36 which may be fastened in an adjusted position on the ring 35 which in turn is supported by rods 34 mounted in the control carriage 31. The bars 24 and 25 reciprocate through the slot 19 of gear 18 to control the pattern and thus a variety of ornamental grooves may be cut in the work element "W", the cutter being operable over a straight or irregular peripheral surface. Reversely convoluted bars 24 and 25 may be alternately used for producing reversely disposed helical groovers in the article ornamented. Also the convoluted bars may be removed entirely to make parallel flutes.

While cutting ovate-oblong or irregular peripheral surfaces, the screw 30 in Fig. 3 is replaced by pin 29 and spring 39 leaving the cutter free to slide vertically on the guide rods 34 as the head stock or control carriage 31 in Fig. 3 is moved over the irregular surfaces in a horizontal position. Depth washers on each of the cutters rest on top of wood while cutter is fluting to the proper depth.

55 The cross section drawing of Fig. 3 shows how the convoluted bars 24 and 25 are cut away to hinge when the one end of the longitudinal guide bar is elevated in a vertical position to cut over tapered peripheral surfaces. The interchangeable convoluted bars 24 and 25 are fastened by the stud 26 to the carriage 31 and either one of these bars traversed by hand in a horizontal position through the guide-way in bearing 19 reciprocating and with gear 18 is synchronized 60 with the lathe spindle through the pull-pin 13, to give clockwise and counter-clockwise motions.

In Fig. 6 a bearing base 20b the same height as lathe center, on bearing lock nut 20, is fastened to a change gear by screws 16. In the back of 19 screw 20c is put in place and convoluted bar is removed, this locking the lathe spindle with the gears. Compound rest 36 is set 90 degrees to cut parallel longitudinally spur convexo-concave or irregular peripheral surfaces.

75 Perforated index plate 9 in Fig. 6 works inside

of the fingers or sector 15a of member 15 and is fastened to the lathe spindle by set screw 22. Sector or plate 15 carries a pull-pin 13 held in engagement with a perforation in the index plate by spring 14. Work being synchronized the pull-pin 13 is pulled out and the periphery of the work advanced on the lathe center to start the next cut. The flexible shaft member 41, shown in Fig. 1, is fastened in compound rest 36 by screw 27 in fixed spots to give the various angles and center the cutter on the helix angle that is to be cut. By the handle 28, and rapid screw 30 takes the cutter downward into the work and is removed when returning the head stock or carriage 31 to stop 44 (or stop 45). Simple indexing as heretofore described is completed and operation continued.

The pin 29 (with its spring 39) works between the guideways 34 and head stocks 31 (when substituted for screw 30 shown in Fig. 3) to keep a tension on the flexible shaft and cutter while going over irregular surfaces.

Standing in vertical position the head stock or carriage 31 in Fig. 3 has a precision alignment by screws 32 to adjust the head stock on the longitudinal section guide-way 1. Member 33 in Fig. 3 is a lock screw holding the guide rods 34 in place while cutting straight or tapered peripheral surfaces.

I provide collars 47, as shown in Fig. 1 arranged on each side of the cutter 40 to rest on top of the wood, each side of the flute being cut to control the depth of the cut.

What I claim is:

1. In a wood carving attachment, the combination with a lathe having a tail stock and head stock of rods extending longitudinally of the frame of the lathe, a rest and guide adjustably attached to the underside of the frame of the lathe and supporting said rods in a laterally adjustable relation thereto, a control carriage slidably mounted on said longitudinal rods, a vertically movable device adjustably mounted in the control carriage, a flexible shaft, a compound rest swivelly mounted on said device and adapted to support the flexible shaft, and a cutter carried by said flexible shaft, a screw having its unthreaded portion mounted in the aforesaid vertically removable device and having its threaded portion mounted in the control carriage, and a handle on the end of said screw for rapid operation of same, a convoluted bar having one of its ends pivotally connected to the control carriage, a gear having a central guideway slot of suitable size to receive the convoluted bar and permit it to slide therethrough, a second gear in mesh with the first gear, a casing affixed to and rotating with said gear, a disk loosely mounted in the casing and having annular spaced perforations which may be releasably engaged to cause the said perforated disk to rotate with the casing, said perforated disk also having a hub, and a set screw in said hub to secure the disk to the rotating shaft of a lathe.

2. In a wood carving attachment, the combination of rods extending longitudinally of the frame of a lathe, a rest and guide adjustably attached to the underside of the frame of a lathe and supporting said rods in a laterally adjustable relation thereto, a control carriage slidably mounted on said longitudinal rods, a vertically movable device adjustably mounted in the control carriage, a flexible shaft, a compound rest swivelly mounted on said device and adapted to support the flexible shaft, a cutter carried by

- said flexible shaft, a convoluted bar having one of its ends connected to the control carriage, a gear having a central guideway slot of suitable size to receive the convoluted bar and permit it to slide therethrough, a second gear in mesh with the first gear, a casing affixed to and rotating with said gear, a disk loosely mounted in the casing and having annular spaced perforations which may be releasably engaged to cause the 5 said perforated disk to rotate with the casing, said perforated disk also having a hub, and a set screw in said hub to secure the disk to the rotating shaft of the lathe.
3. In a wood carving attachment, the combination of rods extending longitudinally of the frame of a lathe, a rest and guide adjustably attached to the underside of the frame of a lathe and supporting said rods in a laterally adjustable relation thereto, a control carriage slidably mounted 10 on said longitudinal rods, a vertically movable device adjustably mounted in the control carriage, a flexible shaft, a compound rest swivelly mounted on said device and adapted to support the flexible shaft, a cutter carried by 15 said flexible shaft, a screw having its unthreaded portion mounted in the aforesaid vertically movable device and having its threaded portion mounted in the control carriage, and a handle on the end of said screw for rapid operation of 20 the same.
5. In a wood carving attachment, the combination of rods extending longitudinally of the frame of a lathe, a rest and guide adjustably attached to the underside of the frame of the 25 lathe and supporting said rods in a laterally adjustable relation thereto, a control carriage slidably mounted on said longitudinal rods, a vertically movable device adjustably mounted in the control carriage, a guide way lock nut, a flexible 30 shaft, a compound rest swivelly mounted on said device and adapted to support the flexible shaft, a cutter carried by the flexible shaft, a removable pin and a spring mounted in the aforesaid vertically movable device to keep a tension on the 35 flexible shaft and cutter while going over irregular surfaces, a perforated convoluted helical bar which may be operatively connected to the control carriage, a gear having a central guide way slot of suitable size to receive the convoluted bar and permit it to slide therethrough, a change gear lock nut or screw, a second gear in mesh with the first.
4. In a wood carving attachment, the com-

PERCY B. PYLE.
